MASS SPECTROMETER

John G. Skinner, Corvallis, Oreg., assignor to Phillips Petroleum Company, a corporation of Delaware

Application November 10, 1955, Serial No. 546,221

8 Claims. (Cl. 250—41.9)

This invention relates to sample inlet and evacuation systems for mass spectrometers. In another aspect it relates to electrode mounting means for vacuum tubes.

In recent years mass spectrometers have been developed from highly specialized academic research instruments for measuring the relative abundance of isotopes into analytical tools of extreme sensitivity and accuracy. At the present time, applications are being found for the use of mass spectrometers in process monitoring and control. Mass spectrometry comprises, in general, ionizing a sample of material under investigation and separating the resulting ions according to their masses to determine the relative abundance of ions of selected masses. The material to be analyzed usually is provided as a gas which is bombarded by a stream of electrons to produce the desired ions. Although both positive and negative ions may be formed by such electrical bombardment, most mass spectrometers make use of only the positive ions. These positive ions are accelerated out of the region of the electron beam by means of negative potentials. Such potentials impart equal kinetic energies to ions having like charges such that ions of different masses have different velocities after passing through the electrical field and, consequently, have different momenta.

An important feature of the present invention resides in a combination sample inlet and evacuation system for a mass spectrometer which minimizes the number of glass-to-metal seals in the tube. This is important to reduce leak possibilities. The vacuum pump inlet is connected by a metal tube to the glass spectrometer tube. The sample inlet conduit extends into the tube through the evacuation outlet. Another feature of this invention resides in an electrode mounting structure which eliminates microphonics. The collector plate is secured to a shield plate so as to engage a plurality of spring biased spacer balls. This provides a flexible assembly which can accommodate temperature fluctuations.

Accordingly, it is an object of this invention to provide an improved sample inlet and evacuation system for a mass spectrometer.

A further object is to provide improved electrode mounting means for use in vacuum tubes.

Other objects, advantages and features of this invention should become apparent from the following detailed description taken in conjunction with the accompanying drawing in which:

Figure 1 is a schematic representation of a mass spectrometer incorporating features of this invention;

Figure 2 is a detailed view of the collector plate mounting assembly; and

Figure 3 is a detailed view of the sample inlet and tube evacuating system.

Referring now to the drawing in detail and to Figure 1 in particular, there is shown a mass spectrometer tube 10 comprising a gas impermeable envelope, the interior of which is maintained at a reduced pressure by a vacuum pump, not shown, which communicates with the interior

2

of tube 10 through a conduit 11. A sample of gas to be analyzed is directed into tube 10 through a conduit 12. An electron emitting filament 13 is disposed in one end of tube 10 and an ion collector plate 14 is disposed in the second end of the tube. The end terminals of filament 13 are connected to the respective end terminals of the secondary winding 15 of a transformer 16. The end terminals of the primary winding 17 of transformer 16 are connected to an alternating current source 18. The center tap of the secondary winding 15 of transformer 16 is connected to a negative potential terminal 19.

The gas sample supplied through conduit 12 diffuses into an ionization chamber 22 in tube 10 which is defined by a pair of spaced grids 23 and 24 that are maintained at ground potential. Electrons emitted from filament 13 are accelerated into chamber 22 by the potential difference between filament 13 and grids 23 and 24. A grid 26 is positioned between filament 13 and grid 23. Grid 26 is connected to the output of an emission regulator circuit 27, while can be of the type disclosed in the co-pending application of M. C. Burk, Serial No. 412,790, filed February 26, 1954, now U.S. Patent No. 2,792,500. The input of emission regulator 27 is connected to the center tap of transformer winding 15. This emission regulator is provided for the purpose of applying a potential to grid 26 of magnitude such as to maintain a constant flow of electrons into ionization chamber 22 irrespective of minor fluctuations in the electron emission from filament 13. In this manner the rate at which gas molecules are ionized in chamber 22 by electron bombardment is a function of only the gas pressure in the chamber.

A first collimating electrode 28 is positioned on the second side of ionization chamber 22 and is connected to the contactor of a potentiometer 20. One end terminal of potentiometer 20 is connected to a negative potential terminal 21, the second end terminal of potentiometer 20 being grounded. A second collimating electrode 28' is spaced from electrode 28. Electrode 28' is connected to the contactor of a potentiometer 20'. The end terminals of potentiometer 20' are connected to terminal 21 and ground, respectively.

The positive ions produced in ionization chamber 22 are accelerated by the negative potentials applied to electrodes 28 and 28' so as to travel through the tube toward collector plate 14. A first set of three equally spaced grids 35, 36 and 37 is positioned in tube 10 between grid 28 and collector plate 14; a second set of equally spaced grids 38, 39 and 40 is positioned in spaced relation with the first set of grids; a third set of equally spaced grids 42, 43 and 44 is positioned in spaced relation with the second set of grids; a fourth set of equally spaced grids 45, 46 and 47 is positioned in spaced relation with the third set of grids; and a fifth set of equally spaced grids 49, 50 and 51 is positioned in spaced relation with the fourth set of grids. Grid 35 is connected to the contactor of a potentiometer 29. One end terminal of potentiometer 29 is connected to a negative potential terminal 30, the second end terminal of potentiometer 29 being connected to ground. The contactor of potentiometer 29 can be adjusted to apply selected negative accelerating potentials to grid 35. Grids 36, 39, 43, 46 and 50 are connected to one another and to the output terminal of an electronic switch 55. The input terminal of switch 55 is connected to one output terminal of a radio frequency oscillator 56. Switch 55 is controlled by the output of a square wave generator 57, which in turn is energized by the output of an audio oscillator 58. Switch 55 is thus turned on and off at the frequency of oscillator 58 to apply the output of oscillator 56 to grids 36, 39, 43, 46 and 50. Grid 35 is connected to one output terminal of a step back de-

ductor 61, which in turn is connected to an output terminal of oscillator 56. The second output terminal of detector 61 is connected to grid 51. Grids 35 and 51 are connected to one another by a voltage dividing network 63 which comprises five resistors 64, 65, 66, 67 and 68 that are connected in series relation. Grids 37 and 38 are connected to one another and to the junction between resistors 64 and 65; grids 40 and 42 are connected to one another and to the junction between resistors 65 and 66; grids 44 and 45 are connected to one another and to the junction between resistors 66 and 67; and grids 47 and 49 are connected to one another and to the junction between resistors 67 and 68.

A plurality of closely spaced stopping grids 70 is positioned between grid 51 and collector plate 14. Grids 70 are connected to one another and to the output of a stopping detector 71, which in turn is connected to an output of oscillator 56. A plurality of suppressor grids 72 is positioned between grids 70 and collector plate 14. Grids 72 are connected to a negative potential terminal 73 to suppress secondary electrons which may result from ions impinging upon metal parts of the tube. A grounded shield 75 is positioned adjacent collector plate 14.

Collector plate 14 is connected to one input terminal of an amplifier 76 which is tuned to pass signals of the same frequency as the frequency of oscillator 58. The second input terminal of amplifier 76 is connected to ground. The output terminals of amplifier 76 are connected to first input terminals of a phase detector 77. The second input terminals of phase detector 77 are connected to output terminals of oscillator 58. The output terminals of phase detector 77 are connected to a suitable indicating means such as a recorder 78.

The circuits illustrated schematically in Figure 1 are described in detail in the copending application of M. C. Burk and F. W. Karasek, Serial No. 480,698, filed January 10, 1955, now U. S. Patent No. 2,761,974.

Details of the collector plate assembly are illustrated in Figure 2. Plate 14 is attached by a hub 110 and a screw 111 to a support rod 112. Screen plate 75 has an elongated tube 113 integral therewith which fits on a tube 114 that is sealed to spectrometer tube end 104 at its outer end. Rod 112 is sealed in tube 114 by a plug 115. Plate 75 has a plurality of openings 117 therein. An annular spring 118 is welded to plate 75 so as to extend through openings 117. The portions of spring 118 which extend through the openings in plate 75 form seats to receive insulating balls 120. Balls 120 engage plate 14. Tubes 113 and 114 are held together by a clamp 121. In constructing the mass spectrometer tube, tube 114 is sealed into glass member 104. Rod 112 is sealed in plug 115. Tubes 113 and 114 are then pushed together so that plate 14 engages balls 120 and are secured in place by clamp 121. It has been found that this particular structure is durable and eliminates microphonics. Glass end 104 is sealed to the remainder of the tube after the grid structure is inserted.

The sample inlet tube evacuation system is illustrated in Figure 2. A metal sleeve 125 is sealed to a glass nipple 126 of tube 10. There are only two glass-to-metal seals in the system. This minimizes the danger of leaks. A third seal is required if the filament is removable, as illustrated. A first flange 127 is welded to sleeve 125. A second flange 128 is welded to an outlet pipe 11 which communicates with a vacuum pump, not shown. An annular plate 130 is positioned between flanges 127 and 128 and is secured in place by a plurality of bolts 131. Gaskets 132 and 133 are employed to make a tight seal. Gas sample inlet tube 12 is welded to and extends through plate 130. The inner end of tube 12 extends into spectrometer tube 10. The gas to be analyzed diffuses from tube 12 into the ionization chamber.

From the foregoing description of a preferred em-

bodiment of this invention, it should be apparent that there is provided a mass spectrometer tube having several improvements. The gas sample is introduced and the tube is evacuated through a single opening. This reduces the danger of leaks developing. The collector plate is positioned by a novel mounting structure which remains firm despite temperature changes in the tube and which eliminates microphonics.

While the invention has been described in conjunction with a present preferred embodiment, it should be evident that it is not limited thereto.

What is claimed is:

1. A mass spectrometer comprising a glass envelope having an opening therein, a first metal tube sealed to said envelope to communicate with said opening, a first flange on the end of said first tube remote from said envelope, a second tube having a flange at one end thereof, the second end of said second tube being adapted to be connected to a vacuum pump, a plate having an opening therein, means to seal said plate between said flanges, a third tube extending from a region exterior of said envelope through said plate and said first tube to the interior of said envelope, said second tube being sealed in said plate and being adapted to introduce a sample of gas to be analyzed into said envelope, means to ionize the gas sample, a collector plate in said envelope, and means to direct ions of predetermined mass to said collector plate.

2. A charged particle collector assembly comprising a support plate having a plurality of openings therein, a spring attached to said plate and extending through said openings, an ion collector plate, a spacer positioned adjacent each of said openings in engagement with said spring, and means securing said collector plate to said support plate so that said collector plate engages said spacers against the force of said spring.

3. Apparatus to introduce a gas sample into and to evacuate a mass spectrometer tube comprising conduit means sealed to the spectrometer tube to communicate at one end with the interior thereof, the second end of said conduit means being adapted to be connected to a vacuum pump, and a tube to supply a gas sample extending from a region exterior of said spectrometer tube to the interior thereof through at least a portion of said conduit means.

4. A charged particle collector assembly comprising a first tube, a rod extending through said first tube, sealing means mounting said rod in said first tube in spaced relationship therewith, a collector plate attached to one end of said rod, a second tube enclosing at least a portion of said first tube, a second plate secured to the end of said second tube adjacent said collector plate, said second plate having a plurality of openings therein, a spring attached to said second plate and extending through said openings toward said collector plate, a spacer positioned adjacent each of said openings in engagement with said spring, and means to secure said second tube to said first tube so that said collector plate engages said spacers against the force of said spring.

5. The combination in accordance with claim 4 wherein each of said spacers comprises a sphere of insulating material.

6. A mass spectrometer comprising a gas impermeable envelope defining a spectrometer tube, conduit means sealed to the spectrometer tube to communicate at one end with the interior thereof, the second end of said conduit means being adapted to be connected to a vacuum pump, a tube to supply a gas sample extending from a region exterior of said spectrometer tube to the interior thereof through at least a portion of said conduit means, means to ionize molecules of gas supplied to said spectrometer tube, a support plate in said spectrometer tube, having a plurality of openings therein, a spring attached to said plate and extending through said openings, an ion collector plate, a spacer positioned

adjacent each of said openings in engagement with said spring, means securing said collector plate to said support plate so that said collector plate engages said spacers against the force of said spring means to direct ions of predetermined mass to said collector plate, and means to measure ions impinging upon said collector plate.

7. A mass spectrometer comprising a glass envelope having an opening therein, a first metal tube sealed to said envelope to communicate with said opening, means to attach a vacuum pump to said first tube, a second tube extending through at least a portion of said first tube into said envelope through said opening to introduce a sample of gas to be analyzed, means to ionize molecules of gas supplied to said spectrometer tube, a support plate in said spectrometer tube having a plurality of openings therein, a spring attached to said plate and extending through said openings, an ion collector plate, a spacer positioned adjacent each of said openings in engagement with said spring, means securing said collector plate to said support plate so that said collector plate engages said spacers against the force of said spring, means to direct ions of predetermined mass to said collector plate, and means to measure ions impinging upon said collector plate.

8. A mass spectrometer comprising a glass envelope having an opening therein, a first metal tube sealed to said envelope to communicate with said opening, a first flange on the end of said first tube remote from said envelope, a second tube having a second flange at one end thereof, the second end of said second tube being

adapted to be connected to a vacuum pump, a plate having an opening therein, means to seal said plate between said flanges, a third tube extending from a region exterior of said envelope through said plate and said first tube to the interior of said envelope, said second tube being sealed in said plate and being adapted to introduce a sample of gas to be analyzed into said envelope, a third tube secured to said envelope and extending into said envelope, a rod extending through said third tube, sealing means mounting said rod in said third tube in spaced relationship therewith, a collector plate attached to the inner end of said rod, a fourth tube enclosing at least a portion of said third tube, a second plate secured to the end of said fourth tube adjacent said collector plate, said second plate having a plurality of openings therein, a spring attached to said second plate and extending through said openings toward said collector plate, a spacer positioned adjacent each of said openings in engagement with said spring, means to secure said fourth tube to said third tube so that said collector plate engages said spacers against the force of said spring, means to ionize the gas sample, means to direct ions of predetermined mass to said collector plate, and means to measure ions impinging upon said collector plate.
